Application March 14, 1933, Serial No. 660,733,
and in Germany August 22, 1931

8 Claims. (Cl. 199—4)

This invention relates to a matrix release device for matrix-setting and type-line-casting machines with matrix bars suspended on wires. The new release device is more particularly suitable for machines in which the matrices are guided in a closed circuit, and therefore the matrix bars to be distributed, which are in motion, drop behind the stationary ones in the magazine the whole weight of the matrix bars hanging in the magazine and tending to fall downwards being supported by the stop mechanisms. The new release device owing to its simple and strong construction can, however, be also used with advantage in the well known setting-machines without matrix circulation. The use of the bifurcated levers known in these latter machines and receiving between them the eye of the matrix bar which is first at that time, for stopping or releasing the matrices, has proved unfavourable in setting machines provided with matrix circuit. In these release devices the bars remaining behind in the position of rest are as a rule pushed back also during the release of the foremost matrix, whilst each released matrix starts moving on the inclined guide wire exclusively under the action of gravity. This produces an unsteady falling of the released matrices, a heavy working of the stop mechanism and considerable wear and tear of the same, so that loosening and bending are liable to occur, which loosening and bending are frequently the cause of failure to release or of an unintentional release of several matrices, and other troubles.

In setting-machines without matrix circuit, these drawbacks of the well known brake mechanisms were not noticeable to the same extent, as the matrix bars returning from the setting or casting point get behind the corresponding stop mechanisms from the front whilst the latter, unlike in setting-machines with matrix circuit, are completely relieved from the matrix bars standing still in the magazine, and therefore are not exposed to any strains.

The present invention avoids these drawbacks in a simple and reliable manner by imparting to the eye of the released matrix bar, at the moment of its release, a shock, that is to say, an initial acceleration, in the direction of its sliding along the guide wire, whilst the matrices remaining behind the stop mechanism are not moved. Moreover, care is taken to ensure by a suitable construction that only one matrix bar shall be released at each release movement of the device, whilst by means of a suitable support, the bearings of the stop mechanism are also re-

lieved from the pressure of the stationary matrix bars behind it, and the frictional resistances produced during the movement of the stop mechanism, are reduced to a minimum.

Two constructions of the new release devices are shown by way of example in the accompanying drawing, in which:

Figure 1 is an elevation of the device in its initial position;

Figure 2 is a similar view, but with the device in the release position;

Figure 3 is a side elevation of Figure 2, the sliding down of the matrix just released being also indicated;

Figure 4 shows in elevation another construction of the device;

Figure 5 is a side elevation of Figure 4;

Figure 6 shows on an enlarged scale the locking parts at the bottom end of the release lever;

Figure 7 is a section on line VII—VII of Figure 6, showing on an enlarged scale a few matrix eyes on the guide wire, and

Figures 8a to 8d show on an enlarged scale the various phases of the release process.

The device comprises a block 1 secured to the machine frame and a release lever 2 which is mounted so that it can rotate to a limited extent about a pin 3 secured to the block 1. The lever 2 is controlled by the action of a spring 4 which tends to keep it in its position of rest.

With the upper end of the release lever 2 engages a pull wire 5 leading to the keys (not shown). The lateral movement of the lever 2 is limited by a pin 6 secured to the block 1, which pin projects into an aperture 7 of larger diameter in the lever 2. In order to reduce the frictional resistance during the movement of the release lever 2 which is pressed by the stationary matrices against the block 1, and in order to relieve

at the same time the pivot pin 3, the block 1 is carried down to the bifurcated bottom end of the release lever 2 and provided at the lowermost point with a separate engagement face 8 (Figures 1 to 3). A similar engagement face is provided around the pivot pin 3, and both engagement faces are separated from each other by a recess in the block 1 so that the lever 2 has reliable bearings at two different points. The frictional resistance to be overcome during the movement of the block 2 can be preferably reduced still more by arranging at the bearing face 8 a steel ball 11 (see Figures 4 and 5) movable in a slot 10 in the block 1.

According to the invention, the bottom end of the lever 2 is bifurcated so as to form two parts

12 and 13. One part 12 is situated in the extension of the lever 2, and the other part 13 is cranked or bent out towards the stationary matrices. The part 12 is given a prismatic shape, 5 and the cranked part 13 has the wedge-shaped form indicated in Figures 6, 7 and 8. The front edge of the part 13 facing the matrices is made sharp like a knife, whilst its side away from the matrix eyes is equal to the full thickness of the 10 release lever 2. The dimensions are calculated in such a manner that the eye of a single matrix bar just fits into the gap 14 between the parts 12 and 13.

On a key being depressed, the lever 2 is 15 turned by means of the pull wire 5 about the pin 3 from its position of rest (Figure 1) to the working position (Figure 2), one matrix bar being thereby released. During this release movement of the lever 2, the oblique inner surface 18 formed 20 by the wedge shaped part 13, imparts to the matrix 16 to be released, at the moment of its release, an initial acceleration in the direction of its sliding along the guide wire 17 (see Figures 8a to 8d). The straight surface 15 of the part 25 13, facing the matrix bars not to be released, extends according to the invention parallel to the matrix eyes so that during the process of release, the matrix bars situated behind it, are not moved.

30 After the release of a matrix bar, the lever 2 is returned to its position of rest (Figure 1) by the spring 4, the fork part 13 releases the matrices held back which now slide down to an extent equal to the width of a matrix bar on the sliding 35 wire 17, so that the foremost matrix again engages with the part 12 which is in its position of rest (Figure 1) and fills up the gap 14.

Having now fully described the said invention what is claimed and desired to be secured by 40 Letters Patent is:

1. A matrix release device for matrix-setting and type-line-casting machines of the type having matrix bars guided and suspended on wires, including a pivotally mounted resiliently controlled forked member normally arranged adjacent each of the wires and including two limbs one of which acts to stop the movement of the matrix bars thereon while the other limb is offset therefrom and wedge-shaped for engaging 45 and separating only the foremost matrix bar and imparting an initial movement thereto as it is released upon the swinging of said member whilst the matrix bars left behind the release device are not moved.

2. A matrix release device for matrix-setting and type-line-casting machines having matrix bars provided with eyes and guided and suspended on wires, the foremost matrix bar of which at any time is stopped or released, said device including a block fixed to the frame of the machine, a lever pivotally mounted for limited movement on the block having one end forked for engagement with the eye of the foremost matrix bar, a spring for normally holding the lever in a position to prevent movement of the matrix bars, one limb of the forked end of the said lever engaging between the first and the

second matrix and being formed into a wedge with the back surface parallel to the matrix eyes, so that the forked end of the lever seizes at each release movement only one matrix eye and imparts to it an initial acceleration in the direction of its sliding along the guide wire, whilst the matrix bars left behind the release device are not moved.

3. A device as claimed in claim 2, wherein the limb of the forked end of the lever preventing in the position of rest the sliding down of the matrix bars suspended in the magazine, is in the same plane as the lever, whilst the other limb keeping back in the working position the non-released stationary matrices in the magazine, is bent out of the plane of the lever towards the magazine in the form of a hook in such a manner that a gap sufficient to receive the eye of only one matrix bar is produced between the said two limbs.

4. A device as claimed in claim 2, wherein the wedge-shaped part of the forked end of the release lever is offset to provide a gap and is provided with a knife edge at its front edge facing the matrix guide wire for the purpose of facilitating the separation of the matrices to be released, whilst its back surface away from the matrices has the thickness of the release lever, so that an oblique inner surface of the limb is formed which constitutes a boundary of the gap and starts the movement of the matrix to be released.

5. A device as claimed in claim 2, wherein the lever is provided with an opening and a pin carried by the block and of less diameter than the opening and projecting into the larger opening for the purpose of limiting the lateral deflection of the said lever.

6. A device as claimed in claim 2, wherein a support is provided at the bottom end of the block immediately about the fork for relieving the bearing of the lever from the pressure of the matrix bars suspended behind the fork.

7. A device as claimed in claim 2, wherein a support is provided at the bottom end of the block immediately above the fork for relieving the bearing of the lever from the pressure of the matrix bars suspended behind the fork, and said block being provided between said support and the pivot point of the lever with a recess for the purpose of reducing the friction produced during the movement of the lever.

8. A device as claimed in claim 2, wherein a support is provided at the bottom end of the block immediately above the fork for relieving the bearing of the lever from the pressure of the matrix bars suspended behind the fork, and said support being also provided with means for further reducing friction and of facilitating the movement of the release lever, in the form of a ball bearing which comprises a recess provided in the block and a steel ball mounted in the said recess in an easily movable manner, and against which ball rests the bottom end of the lever.

JULIUS DORNETH.
